(57) **CLAIM**

The ornamental design for a toy vehicle, as shown and described.

DESCRIPTION

FIG. 1 is a perspective view of a toy vehicle having a straight tire and having my design;

FIG. 2 is a front view of the toy vehicle of FIG. 1;

FIG. 3 is a rear view of the toy vehicle of FIG. 1;

FIG. 4 is a left side view of the toy vehicle of FIG. 1;

FIG. 5 is a right side view of the toy vehicle of FIG. 1;

FIG. 6 is a top view of the toy vehicle of FIG. 1;

FIG. 7 is a bottom view of the toy vehicle of FIG. 1;

FIG. 8 is a perspective view of a toy vehicle having a convex tire and having my design;

FIG. 9 is a front view of the toy vehicle of FIG. 8;

FIG. 10 is a rear view of the toy vehicle of FIG. 8;

FIG. 11 is a left side view of the toy vehicle of FIG. 8;

FIG. 12 is a right side view of the toy vehicle of FIG. 8;

FIG. 13 is a top view of the toy vehicle of FIG. 8;

FIG. 14 is a bottom view of the toy vehicle of FIG. 8;

FIG. 15 is a rear view of a third embodiment of a toy vehicle illustrating an environmental tread applied to a straight tire as shown in FIGS. 1-7;

FIG. 16 is a rear view of a fourth embodiment of a toy vehicle illustrating an environmental tread applied to a straight tire as shown in FIGS. 1-7;

FIG. 17 is a rear view of a fifth embodiment of toy vehicle illustrating an environmental tread applied to a straight tire as shown in FIGS. 1-7;

FIG. 18 is a rear view of a sixth embodiment of a toy vehicle illustrating an environmental tread applied to a straight tire as shown in FIGS. 1-7;

FIG. 19 is a rear view of a seventh embodiment of a toy vehicle illustrating an environmental tread applied to a straight tire as shown in FIGS. 1-7;

FIG. 20 is a rear view of an eighth embodiment of a toy vehicle illustrating an environmental tread applied to a straight tire as shown in FIGS. 1-7;

(Continued)

FIG. 21 is a left side view of a toy vehicle illustrating, but not claiming, an environmental wheel applied to a convex tire as shown in FIGS. 8-14; and,

FIG. 22 is a right side view of a toy vehicle illustrating, but not claiming, an environmental wheel applied to a convex tire as shown in FIGS. 8-14.

Features shown in dashed lines are features of the toy vehicle that form no part of the design claimed.

1 Claim, 22 Drawing Sheets
